UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

CENTRIFUGAL FILTER.

Application filed May 4, 1925. Serial No. 27,863.

My invention relates to improvements in centrifugal filters. The object of the invention is to provide a continuous filter which shall be of simple construction, easily maintained, readily accessible internally, and highly efficient.

The structure embodying the invention and the means employed in the attainment of the foregoing objects will be clearly understood on reference to the drawings that form part of this specification; and in which Fig. 1 is a vertical section of a large capacity, centrifugal filter embodying my invention. Fig. 2 illustrates the top of the centrifugal unit or member of the apparatus, as seen from the line 2-2; Fig. 3 is a horizontal section on the line 3-3 of Fig. 1; and Fig. 4 is a horizontal section on the line 4-4 thereof.

The apparatus is of such simple construction that it comprises only four essential parts, namely: the members A, B, C and D. These will be described in detail.

The conical member A is the fluid admission head of the filter, and contains the preferably integral fluid spreading or directing cone A'. The bottom of the cone A' stands slightly above the under surface of the flange A''.

The member C is a removable section which contains the member B. The internal diameter of the member C is the same as the lower end of the member A. The top flange C' of the member C is joined to the member A by the bolts 2. The lower end of the member C contains the internal rib or flange C² having a beveled bottom C³ and containing the large central opening C⁴. As herein shown the lower end of the member B is preferably polygonal, the opening C⁴ is of corresponding shape to receive it.

The top of the member C is provided with sinks or notches C⁵ that will be referred to later. The lower end of the member C is marked by the flange C⁶.

The member D is bulbous in shape to provide a large collection cavity D' and has a top or neck portion D². The latter is marked by the top flange D³ which is connected to the flange C⁶ by the bolts 3. At the bottom of the member D is a nipple D⁴ which receives a drain pipe D⁵. The portion D⁶ is a beveled flange or collar surrounding the initial outlet D⁷ of the filter. That outlet

may be tapered as shown. The member D⁶ stands so far below the rib C² as to provide a circumferential gap or race D⁸ which is in direct communication with the cavity D' through the annular opening or slot D⁹ between the periphery of the flange D⁶ and the neck portion D². The terminal outlet D¹⁰ of the filter is preferably in the side of the part D and is connected with the opening D⁷ by the integral elbow or curved pipe D¹¹. This construction is convenient for several reasons and makes it possible to employ a central discharge or drain at the bottom of the bulbous pocket D. However, when it is desired the flow of liquid may be directly downward through the bottom of the filter.

The part B is a tangential tuyère ring or barrel which serves to set the downward flowing fluid into rapid rotation in a plane transverse to the longitudinal axis of the filter and directly above the initial outlet D⁷. The ring or barrel B is generally cylindrical being mainly composed of a circumferential series of overlapping tuyère blades B¹. Together these form a large number of slit-like longitudinal and tangential tuyères B² which receive the fluid from the circumferential space C⁷ within the member C. At their lower ends the tuyère blades are notched as shown in Figs. 1 and 3 and are attached to a flat-sided or polygonal ring B². That is the polygonal part which occupies the before-mentioned polygonal hole C⁴ at the bottom of the member C.

The lower ends of the blades rest on the top of the rib C². The upper ends B³ of the blades B¹ are bent outward (see Fig. 1) and are attached to the margin of the top plate B⁴. The bottom of the latter is preferably characterized by a peripheral retaining groove B⁵. For centering the member B in the member C and partly to carry the weight of the member B, I employ projecting arms B⁶ on the top B⁴. The ends of the arms B⁶ are accommodated in the notches C⁵ and the whole top is below the level of the flange A².

The member A is flanged for connection with the inlet pipe 4, likewise the member D is flanged for connection with the outlet pipe 5. These connections are permanent and need not be disturbed when it is desired to remove the member B and get at the interior of the members A, C, and D. For such

purposes the bolts 2 and 3 are removed and the member C is drawn out from between the members A and D. Obviously, the member B is wholly contained within the member C and is removed therewith, and likewise replaced therewith.

The parts being assembled as shown in Fig. 1 and a stream of water or other fluid being admitted at the top, the filtering action at once begins at the member B. As will be apparent the downward flowing fluid is sub-divided into many thin longitudinal streams which enter the member B tangentially and at relatively high velocity. Each stream immediately impacts the angularly disposed succeeding blades B' and the first centrifugal separation of the heavier substances is immediately accomplished. It will be understood that the whole filter is filled with liquid and that the tangential movement of the streams within the member B organizes and maintains a swift whirling action of the fluid therein and also in the circumferential gap or race D⁸. Thereby the initial separation of the heavier from the lighter components of the fluid is maintained and completed. And as the whirling fluid moves downward toward the outlet D⁷ the peripherally separated heavier substances are centrifugally ejected into the circumferential race D⁸, thence to settle into the cavity D'.

Meantime, the purified fluid constantly leaves the filter through the outlets D⁷ and D¹⁰. The heavier substances collected in the cavity D' may be blown off continuously or discharged intermittently, as desired. A

special advantage of the bulbous bottom resides in the fact that the contents thereof takes on a considerable whirling motion 40 from the contents of the race D⁸ and as a result the heavier substances descending through the annular slot or opening D⁹ quickly move outward beneath the overhanging top of the bulbous member D and are 45 thus effectively prevented from returning to the opening D⁹.

Having thus described my invention I claim as new and desire to secure by Letters Patent:—

1. A centrifugal filter comprising a fluid admission head in combination with a collection pocket below the same, a removable member between said head and pocket, a fluid-whirling member wholly contained within the removable member, a central outlet pipe having a lateral flange at its top and positioned in the top of said pocket below the said fluid-whirling member, and a drain for said pocket.

2. A centrifugal filter comprising a conical fluid admission head in combination with a bulbous collecting pocket, an intermediate member joining said head and pocket and which is removable laterally between said head and pocket, a fluid-whirling element positioned in said intermediate member and an outlet pipe positioned in said bulbous member and presenting an outlet orifice centrally below said intermediate member and said fluid-whirling element.

In testimony whereof I have hereunto set my hand this 30th day of April, A. D. 1925.

CHARLES GILBERT HAWLEY.
